US00D935479S

(12) **United States Design Patent** (10) Patent No.: **US D935,479 S**
 Katou et al. (45) Date of Patent: ** Nov. 9, 2021

(54) **DISPLAY SCREEN WITH GRAPHICAL USER INTERFACE**

(71) Applicant: **CKD CORPORATION**, Komaki (JP)

(72) Inventors: **Takaharu Katou**, Komaki (JP);
Kazuyoshi Kikuchi, Komaki (JP);
Atsushi Fukuta, Komaki (JP); **Hiroko Isayama**, Komaki (JP)

(73) Assignee: **CKD CORPORATION**, Komaki (JP)

(**) Term: **15 Years**

(21) Appl. No.: **29/725,228**

(22) Filed: **Feb. 24, 2020**

(30) **Foreign Application Priority Data**

Aug. 28, 2019 (JP) 2019-019116

(51) **LOC (13) Cl.** **14-04**

(52) **U.S. Cl.**

USPC **D14/486**

(58) **Field of Classification Search**

USPC D14/485-495

CPC G06F 3/048-04897

See application file for complete search history.

Solder Paste Inspection Machine VP6000-V VP5200-V Series published by CKD corporation in Sep. 2015 in Japan and U.S.A.; 12 pages.

Primary Examiner — Andrew T Nemeth

(74) Attorney, Agent, or Firm — Cantor Colburn LLP

(57) **CLAIM**

The ornamental design for a display screen with graphical user interface, as shown and described.

DESCRIPTION

The FIGURE is a front view of a display screen with graphical user interface showing our new design.

The broken lines illustrate portions of the display screen with graphical user interface that form no part of the claimed design.

1 Claim, 1 Drawing Sheet
